UNITED STATES PATENT OFFICE.

CHARLES L. HENDERSON, OF APPLETON, WISCONSIN, ASSIGNOR TO ALLIS-CHALMERS MANUFACTURING COMPANY, OF MILWAUKEE, WISCONSIN, A CORPORATION OF DELAWARE.

ROTARY MACHINE.

Refiled for abandoned application Serial No. 43,167, filed July 13, 1925. This application filed August 13, 1927. Serial No. 212,826.

This invention relates in general to improvements in rotary machines, and relates more specifically to improvements in the construction and operation of mechanisms for adjusting the rotor vanes of rotary machines which are capable of either propelling or of being propelled by fluid.

An object of the invention is to provide an improved rotary machine which is simple in construction and efficient in operation. Another object of the invention is to provide improved mechanism for controlling the operation of rotary machines. A further object of the invention is to provide simple and efficient means for effecting angular adjustment of the vanes of a rotor, about their axes. These and other objects and advantages attainable with the present improvements will be apparent from the following description.

Some of the novel features of rotor vane adjusting mechanism shown but not specifically claimed herein, form the subject matter of copending applications Serial No. 35,517, filed June 8, 1925, patented Jan. 10, 1928, No. 1,656,018, and Serial No. 40,136, filed June 29, 1925, patented Jan. 10, 1928, No. 1,656,017.

A clear conception of an embodiment of the present improvements and of the operation of devices constructed in accordance therewith, may be had by referring to the drawing accompanying and forming a part of this specification in which like reference characters designate the same or similar parts in the various views.

Fig. 1 is a central vertical section through a vertical hydraulic turbine installation including an axial flow rotor having adjustable vanes.

Fig. 2 is an enlarged fragmentary central vertical section through a portion of the improved turbine rotor and through a fragment of the main shaft thereof.

Fig. 3 is a top view of a portion of the improved vane adjusting mechanism.

While the invention is specifically shown and described herein as having been applied to an axial flow hydraulic turbine installation, it will be apparent that at least some of the features of the improvements are more generally applicable to the rotors of various types of machines such as pumps, blowers, propellers, steam turbines, etc. The hydraulic turbine unit specifically illustrated

in the drawing comprises in general a rotor 2 having a plurality of pivotally supported 55 vanes 3 radiating from a central hub 4 secured to the lower flange 24 of the lower section 5 of the hollow main shaft; a main turbine casing 6 forming a housing for the rotor 2 and also providing a vane free transition 60 space 8 for conducting water from a penstock or flume 14 toward the rotor 2 in the form of a vortex advancing in an axial direction; and a draft tube 11 for conducting the water from the rotor 2 to the tail-race 12 in a 65 well known manner.

The dovetail-shaped radiating vanes 3 of the rotor 2 which are four in number, are pivotally associated with the hub 4, the inner extremity of each vane 3 being provided with 70 a plurality of concentric circular bearing portions 18, 19, 20 journaled within the hub 4, and the axes of all of these bearing portions lying in a common plane disposed perpendicular to the axis of the rotor 2. The 75 hub 4 is detachably connected to the lower flange 24 of the main shaft 5, and has an integral central projection 21 within which the vane portions 20 are journaled. Each of the vanes 3 has a bevel gear segment 17 formed 80 integral therewith between its bearing portions 19, 20, the lower hub section being formed as a continuous piece coacting with the outer side surfaces of all of the gear segments 17 in order to retain the vanes 3 against 85 displacement away from the hub 4. Located within the lower hollow section 5 of the turbine shaft, is an auxiliary or adjusting shaft 15 which besides passing entirely through the shaft section 5 as illustrated in Fig. 2, also 90 extends downwardly through the central projection 21 of the upper section of the hub 4. A bevel adjusting and locking pinion 16 is secured to the lower extremity of the adjusting shaft 15 and coacts with all of the gear segments 17 of the vanes 3. A removable cap 10 secured to the lower hub section encloses the gearing 16, 17.

The mechanism for effecting adjustment of the vanes 3 about their pivotal axes, is associated with the main shaft within a recess 25 formed between the flanges 22, 23 of the lower and upper main shaft sections 5, 26 respectively. This mechanism comprises a mutilated worm wheel 28 secured to the upper extremity of the internal adjusting shaft 100 105

15 by means of a spline 29, and a worm 27 secured to a countershaft 32 and cooperating with the teeth of the worm wheel 28. The countershaft 32 is retained in position within bearings in the flange 22 by means of a locking pin 31. A jack screw 30 coacts with screw threads in the upper extremity of the adjusting shaft 15 and with a washer which rests upon worm wheel 28. The worm wheel 28 in turn rests upon a wearing bushing secured to the lower shaft section 5.

10 The hollow main shaft with which the rotor 2 is associated, is mounted in suitable bearings in the main casing 6 and in the frame of 15 a generator 9 or other energy translating device. The casing 6 and the generator 9 are supported upon a suitable foundation structure 13 and the casing 6 is disclosed as being provided with an annular series of adjustable 20 guide vanes 7 for controlling the flow and for properly conducting the water from the flume 14 to the transition space 8.

15 During normal operation of the unit the vanes 3 are locked to the hub 4 in an adjusted position, and operating fluid is admitted from the flume 14 past the guide vanes 7 and through the transition space 8 to the rotor 2 from which the water is discharged through the draft tube 11 to the tail-race 12. The 25 quantity of operating fluid thus admitted to the rotor 2 may be varied by adjustment of the guide vanes 7 in a well known manner. The vortex of liquid produced by the guide vane 7 and passing to the 30 rotor 2 from the vane free transition space 8, produces rotation of the shaft sections 5, 26 and of the actuating shaft 15, the rotary motion of the main shaft being transmitted to the rotor of the energy translating 35 device 9.

40 If it is desired to effect angular adjustment of the rotor vanes 13 about their pivotal axes, it is desirable to shut off the flow of operating fluid and to stop the unit. When the 45 rotor 2 is at rest, the vanes 3 thereof may be unlocked by releasing the jack screw 30 with the aid of a wrench inserted through the upper hollow shaft section 26, thereby permitting the internal operating shaft 15 and the 50 pinion 16 to drop slightly and to release the gear segments 17. When the elements have been thus unlocked, the countershaft 32 may be rotated thus causing the actuating shaft 15 to rotate relatively to the shaft section 5 and to adjust the vanes 3 about their pivotal axes. 55 When proper adjustment of the vanes 3 has been thus effected, the jack screw 30 may again be manipulated to move the shaft 15 upwardly within the shaft section 5 thereby 60 jamming the bevel pinion 16 against the gear segments 17 and rigidly locking the vanes 3 in adjusted position.

65 It will be apparent that the vane adjusting mechanism is readily accessible from the exterior of the turbine casing 6 and that the

locking device effectively maintains the vane 3 in adjusted position. By placing the adjusting mechanism within the flanges between the main shaft sections 5, 26, a relatively short actuating shaft 15 may be utilized and 70 undesirable projections are avoided. The actuating mechanism within the flanges 22, 23 is relatively simple in construction and is entirely enclosed, being thus protected against accidental actuation and destruction. It will 75 be understood that ordinarily only slight adjustment of the vanes 3 is desired, but any degree of adjustment may obviously be effected with the improved mechanism.

80 It should be understood that it is not desired to limit the invention to the exact details of construction and operation herein shown and described, for various modifications within the scope of the claims may occur to persons skilled in the art.

85 It is claimed and desired to secure by Letters Patent:

1. In combination, a main shaft comprising sections connected by flanges, a vane pivotally associated with said shaft, an adjusting shaft disposed concentrically of said main shaft, and means located between and entirely within the bounding surfaces of coacting flanges of said sections for rotating said adjusting shaft relative to said main shaft to 95 effect pivotal movement of said vane.

2. In combination, a main shaft comprising sections connected by flanges, a plurality of vanes pivotally associated with a section of said shaft, an adjusting shaft disposed coaxial with said main shaft, and means located between and entirely within the bounding surfaces of coacting flanges of said sections for rotating said adjusting shaft relative to said main shaft to 105 effect pivotal movement of said vanes.

3. In combination, a main shaft comprising sections connected by flanges, a hub secured to one of said sections, a plurality of vanes pivotally supported by said hub, and adjusting shaft disposed coaxial with said main shaft, and means located between and entirely within the bounding surfaces of coacting flanges of said sections for rotating said adjusting shaft relative to said main shaft 110 to effect pivotal movement of said vanes.

4. In combination, a hollow main shaft composed of sections connected by flanges, a plurality of vanes pivotally associated with a section of said shaft, an adjusting shaft disposed within said section of said main shaft, motion transmitting means connecting said adjusting shaft and said vanes, and means located between coacting flanges of said sections and entirely within the bounding surface of said section for rotating said adjusting shaft relative to said main shaft 120 to effect simultaneous pivotal movement of said vanes.

125 5. In combination, a hollow main shaft 130

composed of sections connected by flanges, a hub secured to one of said sections, a plurality of vanes pivotally supported by said hub, an adjusting shaft disposed within a 5 section of said main shaft, motion transmitting means connecting said adjusting shaft and said vanes, and means located between coacting flanges of said sections and entirely within the bounding surface of said sections 10 for rotating said adjusting shaft relative to said main shaft to effect simultaneous pivotal movement of said vanes.

6. In combination, a main shaft composed of hollow sections connected by flanges, a 15 plurality of vanes pivotally associated with one of said shaft sections, an adjusting shaft located within the vane carrying section of said main shaft only, motion transmitting gearing connecting said adjusting shaft with 20 said vanes and means located between and entirely within the bounding surfaces of coacting flanges of said main shaft sections for rotating said adjusting shaft relative to said main shaft to effect simultaneous pivotal 25 movement of said vanes.

7. In combination, a main shaft composed of hollow sections connected by flanges, a hub

secured to one of said sections, a plurality of vanes pivotally supported by said hub, an adjusting shaft located within one of said sections of said main shaft only, motion transmitting gearing connecting said adjusting shaft with said vanes, and means located between and entirely within the bounding surfaces of coacting flanges of said main shaft 30 sections for rotating said adjusting shaft relative to said main shaft to effect pivotal movement of said vanes.

8. In combination, a main shaft composed of hollow sections connected by flanges, a 40 plurality of vanes pivotally associated with one of said shaft sections, an adjusting shaft located within the vane carrying section of said main shaft only, motion transmitting gearing connecting said adjusting shaft with 45 said vanes, and worm gearing located between and entirely within the bounding surfaces of said flanges for actuating said adjusting shaft to effect simultaneous pivotal movement of 50 said vanes.

In testimony whereof, the signature of the inventor is affixed hereto.

CHARLES L. HENDERSON.
